UNITED STATES PATENT OFFICE.

GILES S. CRANSON, OF SILVER CREEK, NEW YORK, ASSIGNOR TO CRANSON,
HUNTLEY & CO., OF SAME PLACE.

GRAIN-SCOURER.

SPECIFICATION forming part of Letters Patent No. 356,273, dated January 18, 1887.

Application filed May 27, 1886. Serial No. 203,332. (No model.)

To all whom it may concern:

Be it known that I, GILES S. CRANSON, of Silver Creek, in the county of Chautauqua and State of New York, have invented new and useful Improvements in Grain-Scourers, of which the following is a specification.

This invention relates to that class of grain-scourers in which the kernels are freed from the adhering impurities by the attrition of the kernels against each other and against metallic surfaces, and which consist, essentially, of a horizontal scouring-case through which the grain passes slowly, and rotating stirrers which move and scour the grain and cause it to rub against the case as the grain passes from the feed to the discharge end of the case.

The object of this invention is to improve the devices whereby the grain is scoured and to regulate the discharge of the scoured grain from the case; and my invention consists, to that end, of the improvements which will be hereinafter fully set forth, and pointed out in the claims.

In the accompanying drawings, consisting of two sheets, Figure 1 is a longitudinal sectional elevation of my improved grain-scourer. Fig. 2 is a cross-section in line *x x*, Fig. 1, on an enlarged scale. Fig. 3 is a cross-section in line *y y*, Fig. 1. Fig. 4 is a longitudinal section of the discharge end of the scouring-case, on an enlarged scale. Fig. 5 is a cross-section in line *z z*, Fig. 1, on an enlarged scale. Fig. 6 is a fragmentary elevation of the scouring-drum. Fig. 7 is a fragmentary cross-section of one of the pivoted scouring-plates. Fig. 8 is a side elevation of one of the stirrers. Fig. 9 is an elevation at right angles to Fig. 8.

Like letters of reference refer to like parts in the several figures.

40 A represents the stationary main frame of the machine; B, the preliminary separating-screen; and C, the separating wind-trunk, through which the grain passes from the screen B to the feed-hopper D.

45 E represents the horizontal shaft, journaled in bearings *e e'*, secured to the frame A, and carrying near one end the fan-blades E', which rotate within a case, E².

F represents the scouring drum or cylinder, 50 secured to the shaft E within the perforated

scouring-case G, which latter is supported on the main frame A by two frames, G' G².

H represents the tight casing inclosing the perforated scouring-case G, and h represents an air-passage formed between the latter and the inclosing-casing H. This passage communicates with one eye of the fan E' by means of openings g, formed in the frame G' and a passage, g', and it receives air through openings g², formed in the frame G².

60 I represents the discharge-chamber, arranged at the rear end of the scouring-case G, and separated from the same by a partition or plate, i, which is provided in its upper portion with a discharge-opening, i'. The inner 65 side of the plate i, which faces the rear end of the scouring-drum F, is provided with an annular row of serrations, i', against which the grain is rubbed before it escapes through the opening i'.

70 J represents a movable valve plate or gate arranged on the outer side of the opening i' in the chamber I, and made movable toward and from the partition i by sliding on pins j.

K represents a horizontal adjusting-bolt, 75 which is secured with its inner end to the plate J, and which carries at its outer end a thumb-nut, j'. The latter bears against the outer side of the final discharge-spout L.

j² represents a spring interposed between 80 the plate J and the frame G², and so as to press the plate J toward the partition i. The plate J is made somewhat smaller than the opening i', so as to leave at the upper edge of the plate a narrow passage through which the 85 grain escapes from the scouring-case through the opening i'. When the grain is fed into the machine so fast that this passage is unable to discharge the grain, the pressure of the grain against the yielding plate J forces the latter 90 away from the partition i, thereby increasing the size of the discharge-passage until the pressure is relieved. As soon as this takes place the spring j² returns the plate to its former position. By this means the grain is held in the 95 scouring-case a sufficient length of time to insure the proper cleaning of the grain, while an undue accumulation of the grain is prevented. The grain which passes into the chamber I through the opening i' is discharged from 100

said chamber through spouts *l* and *l'* into the final discharge-spout *L*.

M represents the stirrers or teeth which are secured to the surface of the scouring-drum *F*.
 5 These teeth are made tapering or wedge-shaped in the direction in which they rotate, and they are arranged with their narrow sides forward, so that they divide the grain as they pass through it. Each tooth is provided in its sides and crown with grooves or corrugations *m*, which increase in depth from the base to the crown of the tooth, and which are separated by plain or blunt surfaces, as clearly represented in Figs. 8 and 9. These teeth
 10 seize the kernels of grain and roll them over and against each other and against the scouring-case as the teeth sweep through the mass of grain, thereby scouring the kernels and detaching the adhering impurities therefrom
 15 without cutting or breaking the grain.
 20

N represents inclined flights, which are secured to the scouring-drum so as to propel the grain from the feed end toward the discharge end of the machine.

25 *O* represents curved scouring-plates hinged or pivoted to the drum *F* on diametrically opposite sides of the same, and in such manner that these plates will be swung outwardly by the centrifugal force, so as to press the grain against the scouring-case. The outward movement of the free end of each plate *O* is limited by bolts *p*, which are secured to the drum *F*, and provided with heads *p'*, against which the plates bear when the outward limit
 30 of the movement has been reached. These bolts are so adjusted on the drum *F* by screw-nuts that the plates will rub the grain properly against the scouring-case and free the grain from adhering impurities without, however,
 35 crushing or cutting the grain, which would be liable to take place in the absence of these stops.

The outer faces of the pivoted scouring-plates *O* are provided with recesses or indentations *q*, which seize the grain and roll it or turn it over repeatedly, so as to thoroughly clean all parts of the grain. These recesses are cheaply formed by constructing each plate of two thicknesses of metal—an outer perforated plate, *r*, and an inner imperforated plate, *r'*, secured together, as represented in Fig. 7. The teeth *M* are arranged upon those portions of the drum *F* which are not covered by the hinged scouring-plates *O*, and these toothed
 40 portions alternate with the scouring-plates.
 45

By my improved scouring mechanism the kernels of grain are rolled over or turned and rubbed or scoured on all sides by a gentle ac-

tion, which thoroughly removes the impurities adhering to the kernels without breaking or cutting the latter.

I claim as my invention—

1. The combination, with a horizontal scouring-cylinder, *G*, provided with a stationary rear plate, *i*, having in its upper portion a discharge-opening, *i'*, of a valve-plate, *J*, adapted to be moved toward and from the discharge-opening, and a spring whereby said valve is pressed toward the discharge-opening, substantially as set forth. 70

2. The combination, with a horizontal scouring-cylinder, *G*, provided with a rear plate, *i*, having a discharge-opening, *i'*, of a movable valve-plate, *J*, adjusting-bolt *K*, spring *j'*, and guide-pins *j*, substantially as set forth. 75

3. The combination, with a scouring-drum, *F*, a perforated scouring-cylinder, *G*, having an elevated discharge-opening, *i'*, and an inclosing tight casing, *H*, of a discharge-chamber, *I*, formed at the discharge end of the scouring-cylinder, and an automatic discharge-valve, *J*, arranged in the chamber *I*, to open and close the opening *i'*, substantially as set forth. 80

4. In a grain-scourer, the combination, with a scouring-case, of rotating stirrer-teeth *M*, made tapering or wedge-shaped in the direction of their motion, and constructed in their sides and crowns with grooves running from the bases to the crowns of the teeth and separated by plain surfaces; substantially as set forth. 85

5. In a grain-scourer, the combination, with a scouring-case, of rotating stirrer-teeth *M*, made tapering or wedge-shaped in the direction of their motion, and constructed in their sides and crowns with blunt corrugations running from the bases to the crowns of the teeth and increasing in depth from the bases to the crowns, substantially as set forth. 95

6. The combination, with the scouring-case, of a scouring-drum, a movable scouring-plate hinged or pivoted to said drum, and a stop whereby the outward movement of the scouring-plate is limited, substantially as set forth. 105

7. The combination, with a scouring-case, of a scouring-drum provided with hinged scouring-plates having indentations or recesses on their outer sides, and projecting corrugated stirrers secured to the drum between the scouring-plates, substantially as set forth. 110

Witness my hand this 22d day of May, 1886.
 G. S. CRANSON.
